UNITED STATES PATENT OFFICE.

JACOB B. ALEY, OF SPOKANE, WASHINGTON.

TOY GUN.

1,231,833.

Specification of Letters Patent.

Patented July 3, 1917.

Application filed September 5, 1916. Serial No. 118,400.

To all whom it may concern:

Be it known that I, JACOB B. ALEY, a citizen of the United States, residing at Spokane, in the county of Spokane and 5 State of Washington, have invented a new and useful Toy Gun, of which the following is a specification.

My invention relates to improvements in toy guns in which pellets are ejected from 10 the barrel by an ejector actuated by a spring, and the objects of my invention are to provide mechanism to eject the pellets from the barrel that will work easily and smoothly, with a minimum of energy exerted by the 15 operator for the amount of force expended upon the pellet.

I attain these objects by the mechanism illustrated in the accompanying drawing, in which—

20 Figure 1 is a plan view of one form of my device; Fig. 2 is a vertical longitudinal section through line 2—2 of Fig. 1; Fig. 3 is a plan view of another form of my device with the stock broken away to show the 25 interior mechanism; and Fig. 4 is a vertical longitudinal section through line 4—4 of Fig. 3.

Similar characters refer to similar parts throughout the several views.

Referring to the drawing, 1 is the stock of a gun having a barrel 2 preferably provided with an opening 3 and tube 4 for feeding pellets into the rear end of the barrel 2. The stock 1 is chambered at 5 to provide a housing for the actuating mechanism, consisting of a lever 6 fulcrumed between its ends on the transverse pin 7, the lower arm of the lever 6 being connected with the spring 8 so mounted as to resist its forward movement, and the upper arm of the lever 6 being pivotally connected with the rear end of the plunger 9 mounted to reciprocate in a central longitudinal aperture through the breech of the barrel 2, the forward end of the plunger 9 in its normal position extending through the breech into the barrel, the forward movement of the plunger 9 being limited by the transverse pin 10 against which the lower arm of the lever 6 normally rests. The upper arm of the lever 6 is pressed backward against the

tension of the spring 8 by a U shaped projection on the crank-shaft 12, which is mounted on suitable bearings 13 and is provided with a handle 14. Alternative forms 55 of the spring 8 are shown, a coil spring in Fig. 2 and a flat spring in Fig. 4. The coil spring shown in Fig. 2 is preferably attached at the rear end to a lever 15 fulcrumed at its end, which is held in position by the ten- 60 screw 16.

The operation of the gun is as follows: Pellets are inserted preferably in the tube 4 to the number that the tube will contain, the lowest one of which, as at 17, rests on 65 the forward end of the plunger 9. The handle 14 is then revolved forward, which brings the U shaped projection 11 into engagement with the upper arm of the lever 6 which presses it backward against the ten- 70 sion of the spring 8 on the lower arm of the lever 6, thus drawing backward the plunger 9 and allowing the pellet 17 to drop down in front of the forward end of the plunger 9. On continuing the revolution of the handle 75 14, the upper end of the lever 6 is pressed backward until it is released by the upward movement of the U shaped projection 11, and the tension of the spring 8 on the lower arm of the lever 6 then causes the upper arm 80 to move rapidly forward, forcing the forward end of the plunger 9 against the pellet 17 and ejecting it from the barrel. This operation can be repeated rapidly as long as pellets remain in the tube 4. 85

Having thus described my invention, what I claim and desire to secure by Letters Patent, is—

A toy gun consisting of a barrel and a stock, a plunger mounted to reciprocate in 90 a central longitudinal aperture through the breech of the barrel, a lever within the stock fulcrumed between its ends, the upper arm of which is pivotally connected with the rear end of the plunger, a spring adapted to 95 hold the lower arm of the lever backward against a stop, and means to press backward and release the upper arm of the lever.

JACOB B. ALEY.
